PROTECTIVE TIP FOR CONCRETE VIBRATORS

Harold E. McCrery, deceased, late of Dayton, Ohio,
by The Winters National Bank and Trust Co.,
and W. Walker Lewis, Jr., executors, Dayton,
Ohio, assignors to Master Vibrator Company,
Dayton, Ohio, a corporation of Ohio

Application June 13, 1950, Serial No. 167,854

4 Claims. (Cl. 259—1)

1

This invention relates to concrete vibrator tools, and more particularly to guard or protective means associated with the tips of such tools.

Concrete vibrators of the small portable tool class are frequently used in the compacting of concrete poured between relatively closely spaced forms to define a wall or the like. For more effective action in such close working areas the end of the tool is frequently fitted with a flanged tip. In the use of the tool, however, it is substantially unavoidable that the tip will strike the forms or the foundation upon which the concrete is being poured. Damage to the tip results therefrom, as well as scoring, denting and deformation of the forms with resulting imperfections in the surface of the finished wall. In an effort to avoid the described disadvantages, it has heretofore been proposed to provide tips having a soft rubber material molded integrally thereon, such tips being substituted for the unprotected tips when their use is deemed desirable. The protection thus afforded is, however, relatively costly. A contractor must keep on hand a supply of the expensive molded tips and upon the development of any flaw in the rubber molding, the entire tip must be discarded and replaced. As a further objection the molded rubber tip while offering the desired protection, reduces the ability of the flanged tip to perform its intended function by altering and making less distinct the configurations thereof.

The instant invention obviates the objections above noted, it being the object of the invention to provide a simple, inexpensive protective device which can be installed on and removed from the tool independently of the tip and which does not alter the shape or function of the tip.

Thus the object of the invention is to simplify the construction as well as the means and mode of operation of protective tips as disclosed herein, whereby such tips may not only be economically manufactured, but will be more efficient and satisfactory in use, adaptable to a wide variety of applications, having a minimum number of parts and be unlikely to get out of repair.

A further object of the invention is to provide a simple, inexpensive sleeve which may be easily assembled upon existing vibrators.

A further object of the invention is to simplify the mode of assembly of such protective tips upon the vibrating tool.

A further object of the invention is to provide a yielding flexible tip for such vibrating tools.

A further object of the invention is to provide an open ended tip for such tools in which the material being vibrated is received for transmission thereto of increased vibratory effect.

5 A further object of the invention is to provide a protective tip of the character described possessing the advantageous structural features, the inherent meritorious characteristics and the mode of operation herein mentioned.

10 With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

15 In carrying out the objects of the invention there is proposed a device in the form of a short length sleeve of resilient deformable material which may be cut from ordinary tube stock, said sleeve being open at its one end to be slipped over the tip and upon the outer end of the tool and open at its opposite end for admission of the material to be vibrated to the tip, the sleeve extending in surrounding protective relation to the tip and overhanging the end thereof.

20 Referring to the accompanying drawing, where-
25 in is found the preferred but obviously not neces-
sarily the only form of embodiment of the invention.

25 Fig. 1 is a view of a concrete vibrating tool, of
the kind to which the instant invention is ap-
plicable, in use;

30 Fig. 2 is a view of the tip end of the vibrating
tool in side elevation, showing the protective sleeve
thereof in longitudinal section;

35 Fig. 3 is an end view of the tip and surrounding
sleeve; and

40 Fig. 4 is a view of the tool with protective sleeve
working in a mass of concrete, showing how the
sleeve prevents contact of the tip with the forms.

45 Like parts are indicated by similar characters
of reference throughout the several views.

Referring to the drawing, there is illustrated in Fig. 1 one manner of use of a portable concrete vibrator. As shown, the vibrator 10 is inserted into a mass of poured, unset concrete 11 confined in forms 12. In accordance with its known construction and mode of operation, the vibrator has an internal eccentric motion, derived through a power supply means 13, compelling a vibratory motion of the tool within the 50 mass of concrete. In response thereto, there is a settling and compacting of the concrete mixture so that it may harden into a solid wall of like characteristics throughout its mass.

55 As seen in Figs. 2 and 4, the outer end of the vibrator 10 is slightly reduced in diameter, being connected to the main body of the tool by a taper

14. Secured to the outer end of the tool, as by welding, screw threads or the like, is a tip 15 commonly used in connection with the tool to induce a more comprehensive churning of the concrete. The base of the tip 15 is reduced in diameter to define with the outer end of the tool 10 a peripheral groove 16. Forwardly of the base thereof, the tip 15 is formed with integral web-like walls 17 and 18 in intersecting ninety degree relation to one another, the peripheral edges of the walls describing approximately paraboloidal curves.

The tip protective device of the invention consists of a sleeve 19 made of resilient, deformable material, for example rubber or rubber substitute. The sleeve 19 is open at both ends and is installed by slipping its one end over the tip 15 and on to the outer reduced end of the tool, the sleeve being expanded by such action and gripping the end of the tool for a secure yet detachable mounting. As installed the sleeve extends in surrounding, protective relation to the tip 15, having a bearing on the approximately parallel portions of the walls 17 and 18. The length of the sleeve is such as to exceed the combined lengths of the reduced outer end of the tool and of the tip 15. Accordingly, the outer end of the sleeve lies unsupported in projecting overhanging relation to the tip 15.

By reason of its being stretched over the tip and tool end the material of the sleeve tends to contract in the region of the peripheral groove 16 to define therewith a detent further resisting detachment of the sleeve. The inner end of the sleeve is beveled as shown so that it may slide partly along and closely hug the taper 14 on the tool end. Moreover, such beveled edge reduces the resistance to withdrawal of the tool from the concrete, helping to avoid the possibility that the sleeve will be dislodged by such withdrawal. Both ends of the sleeve may be beveled, as here illustrated, in which case it is immaterial which end thereof is slipped onto the tool.

A function of the protective sleeve 19 is illustrated in Fig. 4. As there shown, the tool 10 has been introduced in the concrete 11 at such an angle that there is a probability of the tip 15 striking and denting the forms 12. By reason of the presence of the sleeve 19, however, the forms as well as the foundation upon which the concrete is formed can be contacted only by the relatively soft and yielding material of the sleeve. Inasmuch as the outer end of the sleeve is open and unsupported it is capable of flexure in response to the vibratory motions of the tool resulting in a pumping-like action of the concrete to and from the tip 15.

A feature of the protective sleeve of the invention is its ease of manufacture and replacement. According to one method of manufacture, the sleeves are simply cut off in the desired lengths from rubber tube stock of proper diameter. The beveled ends are formed after cutting or they can be made an integral part of the tube as peripheral grooves, with the cuts being taken through such grooves. The sleeves being relatively inexpensive, but quite satisfactory, a contractor can keep a large number of them on hand and if desirable can further obviate the task of removing and storing a sleeve after use by simply cutting it from the tool for discard.

From the above description it will be apparent

that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described the invention, what is claimed is:

1. A concrete vibrator or like device, including a vibratory tool, a flanged tip on said tool, and an open ended flexible sleeve, detachably received on the end of said tool and extending in surrounding protective relation to said tip beyond the outer end thereof.
2. A concrete vibrator or like device, including a vibratory tool, an agitator tip on the end of said tool presenting intersecting flange edges, and a resilient open ended deformable sleeve received on the end of said tool and extending in surrounding protective relation to said tip beyond the outer end thereof.
3. A concrete vibrator or like device according to claim 2, characterized in that said sleeve is supported on said flanged edges over the length of said tip but is unsupported beyond said tip and is deformable in the operation of the tool to exert a pumping-like action of the material to be vibrated to and from the tip within the sleeve.
4. A concrete vibrator or like device, including a vibratory tool presenting an outer end of reduced diameter, an agitator tip secured to the outer end of said tool and defining with said outer end a peripheral groove, and a resilient open ended deformable sleeve detachably received with a press fit on the outer end of said tool and extending in surrounding protective relation to said tip, said sleeve contracting radially in the region of said peripheral groove to define with said groove detenting means restraining inadvertent removal of the sleeve, and said sleeve further extending beyond said tip for flexure of the unsupported end thereof and to preclude contact of the end of said tip with the work while admitting vibrated material to the tip.
